Attorney

UNITED STATES PATENT OFFICE.

ROY H. LINVILLE, OF SAN ANTONIO, TEXAS.

ADJUSTABLE CLAMP.

Application filed April 17, 1922. Serial No. 554,293.

To all whom it may concern:

Be it known that ROY H. LINVILLE, a citizen of the United States of America, residing at San Antonio, in the county of Bexar and State of Texas, has invented new and useful Improvements in Adjustable Clamps, of which the following is a specification.

The object of the invention is to provide a simple and efficient clamp for use in connection with molding boxes, caissons or forms such as are used in connection with concrete or cement building operations and the like as a means of facilitating the assembling and removal of the forms with the minimum expenditure of time and effort and without that injury to the forms which is incident to the use of nails or spikes and similar relatively permanent securing means commonly used in this connection; and with this object in view the invention consists in a construction and combination of parts of which a preferred embodiment is shown in the accompanying drawings, wherein:—

Figure 1 is a plan view of a clamp embodying the invention applied in the operative position to a concrete molding form.

Figure 2 is a side view of the same.

Figure 3 is a perspective view of one of the fulcrum blocks provided with a pronged jaw.

The clamp consists essentially of a plurality of loops or corner elements 10 designed to engage the corners or angles of the brace members 11 of a form such as that indicated at 12, said corner elements being connected in series by interposed linked elements 13 which are adjustable in length by reason of embodying any desired or required number of links constituting chains, one of the linked members including a fastener by which the required tension may be applied to the structure to hold the parts of the form in their proper relative positions.

Each adjustable member consisting essentially of chain links 13 as above indicated is provided with terminal fulcrum blocks 14 and 15 having a flat inner surface to bear against the surface of the form bar 11 and having a transverse opening 16 constituting a bearing for the adjacent end of a corner loop 10. At the inner end of each fulcrum block there is provided means for connection of the adjacent end of the connecting chain formed by the links 13, the block 14 having an opening 17 for engagement by a terminal

swivel link 18 at one end of said chain, and the block 15 having a pronged jaw 19 for engagement with a link of the chain, so that in order to vary the interval between two bearing blocks and thus vary the length of a side of the clamp, to suit the dimensions of the form in connection with which the clamp is to be used, it is only necessary to engage a different link of the connecting chain with the jaw of one of said bearing blocks. In this way a single clamp composed essentially as above indicated may be adapted to fit forms having a relatively wide range of dimensions.

The fastening device consists of a lever 20 fulcrumed as at 21 upon the inner end of one of the bearing blocks shown at 14 and corresponding in construction with the block 14 as above described and a hook member 22 pivotally connected as at 23 to the lever and having engagement at its nose 24 with a selected link of one of the connecting chains, the pivotal points 21 and 23 being so arranged relative to the line of strain between the two bearing blocks at the side of the clamp which carries the fastener, that when the lever is in the position indicated in Figure 1 an eccentric or dead center lock is provided by reason of the pivotal point 23 being outside of a straight line drawn connecting the pivotal point 23 with the link engaged with the nose 24.

Thus in effect the clamp embodies a plurality of corner loops adapted for arrangement in oblique spanning relation with the corner of a frame and connected by side members consisting of chains having adjustable connection with the loops through the selective engageability of the links of said chains with jaws carried by the loops, and the adaptation in the matter of dimensions of a clamp of this construction to the form in connection with which it is to be used can be accomplished without the use of tools and under such conditions as to insure subjecting the form to a compressive strain which will insure retaining its members in proper relative positions until the cement has become set. The release of the clamps and ends of the elements of the form for use in connection with a subsequent operation can be accomplished merely by moving the lever of the fastener outward sufficiently to break the eccentric lock which has been produced in the application of the fastener.

Having described the invention, what is claimed as new and useful is:—

1. A clamp for the purpose indicated having a series of corner loops connected by interposed side members, one of which includes a fastener having means for effecting an eccentric or dead center lock.
2. A clamp having a series of corner loops connected by interposed side members having adjustable connection at one end with the adjacent loop, and a fastener for applying tensile strain to the connected series of links, bearing blocks being interposed between the extremities of the side members and said loops.
3. A clamp having a series of corner loops connected by interposed side members having adjustable connection at one end with the adjacent loop, and a fastener for applying tensile strain to the connected series of links, bearing blocks being interposed between the extremities of the side members and said loops.
4. A clamp having a series of corner loops connected by interposed side members having adjustable connection at one end with the adjacent loop, and a fastener for applying tensile strain to the connected series of links, bearing blocks being interposed between the extremities of the side members and said loops.

tensile strain to the connected series of links, bearing blocks being interposed between the extremities of the side members and said loops, and the side members consisting of chains of which the links are selectively engageable with jaws on said bearing blocks.

5. A clamp having corner loops connected in series by interposed flexible side members and including a fastening device for applying tensile strain thereto, each side member embodying a chain and a jaw for selective engagement with the links of the chain.

6. A clamp for the purpose indicated having a series of corner loops connected by interposed side members, one of which includes a fastener having means for effecting an eccentric or dead center lock, and consisting of a lever and a hook pivotally mounted thereon and provided with a terminal nose for engaging the adjacent side member.

In testimony whereof he affixes his signature.

ROY H. LINVILLE.
